(57) **CLAIM**

The ornamental design for a lighted dishwasher door, as shown and described.

DESCRIPTION

FIG. 1 is a perspective view, from the bottom, of a lighted dishwasher door showing our new ornamental design;

FIG. 2 is a front view thereof;

FIG. 3 is a cross sectional view along lines 3-3 of the door shown in FIG. 2; and,

FIG. 4 is an enlarged view of the detail shown in FIG. 3.

The broken lines of the dishwasher door show surrounding structure or environment and do not form part of the claimed design. The radiating broken lines in FIGS. 3 and 4 represent one or more light beams and form no part of the claimed design.

The dotted lines represent the border between claimed and unclaimed subject matter and do not form a part of the claimed design.
